Primary Examiner — Joseph Kukella*Assistant Examiner* — Francis Wilder(74) *Attorney, Agent, or Firm* — Justin Lampel(57) **CLAIM**

The ornamental design for a receiver as shown and described.

DESCRIPTION

FIG. 1 is a front, left and top perspective view of a receiver showing our design;

FIG. 2 is a rear, right and bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is an enlarged view of portion 9 shown in FIG. 1; and,

FIG. 10 is an enlarged view of portion 10 shown in FIG. 1. The broken lines are included for the purposes of illustrating portions of the receiver that form no part of the claimed design.

1 Claim, 10 Drawing Sheets(56)
